ELECTRIC CLOCK

Oscar H. Dicke, Rochester, N. Y., and Robert H. Dicke, Cambridge, Mass.

Original application January 14, 1939, Serial No. 250,964. Divided and this application January 14, 1944, Serial No. 518,270

10 Claims. (Cl. 58—26)

This invention relates to master clocks wherein the master clocks are, during the presence of alternating current, dominated or otherwise regulated by such alternating current. This application is a division of our prior application Ser. No. 398,129, filed June 14, 1941, which is an improvement over the prior applications of O. H. Dicke, Ser. No. 365,584, filed May 23, 1929, now Patent No. 2,248,164, dated July 8, 1941; Ser. No. 441,109, filed April 2, 1930, now Patent No. 2,331,267, dated October 5, 1943; Ser. No. 729,079, filed June 5, 1934, now Patent No. 2,248,165, dated July 8, 1941; Ser. No. 729,080, filed June 5, 1934, now Patent No. 2,185,334, dated January 2, 1940; Ser. No. 239,538, filed November 8, 1938, now Patent No. 2,359,973, dated October 10, 1944; and Ser. No. 245,700, filed December 14, 1938, now Patent No. 2,313,466, dated March 9, 1943, and the prior application of R. H. Dicke, Ser. No. 39,146, filed September 4, 1935, now Patent No. 2,151,317, dated March 21, 1939, and constitutes also a division of our co-pending application Ser. No. 250,964, filed January 14, 1939, which became abandoned on June 21, 1941.

An object of the present invention resides in the provision of master clocks which will operate in sub-synchronism with the frequency of alternating current of regulated frequency so long as current is available and which will keep substantially correct time during a current cessation.

More specifically several of these master clocks each include an oscillatory member which through suitable mechanism drives a time shaft and which includes a local source of energy and means for impulsing such member each time the amplitude of oscillation of such member falls below a predetermined value in such manner that the successive phase shifts produced by such impulses, whether advancing or retarding phase shifts, cause said member to drive said time shaft to very accurately reflect the passing of time, and additionally includes alternating current controlled means for dominating said member so as to operate in synchronism with such alternating current and so as to cause this member to be operated at an amplitude above this predetermined value so that this alternating current controlled means performs a double function of keeping the member in sub-synchronism and of keeping the local source of energy from being dissipated. In one specific embodiment of master clock the oscillation of the oscillating member is kept at or above a predetermined amplitude by an electro-magnet controlled by a mechanical contact and acting directly on such member and in a

second form the electro-magnet is controlled by a mercury contact which is closed only if the amplitude of such member is below a predetermined value. In one specific form of these master clocks as illustrated it is proposed to dominate the oscillation of such oscillating member through the medium of a very weak spring driven by a synchronous motor, whereas in a second illustrated form such domination is accomplished through the medium of a frequency dividing impulser which creates one impulse for each predetermined number of cycles of alternating current. As shown this frequency dividing impulser is of compound construction in that two frequency dividing impulser are proposed to be used and in which an effective impulse is transmitted only when both of these impulser produce an impulse during the same half cycle of the alternating current. For instance, if one of these impulser produces a current impulse for each fourth positive wave of current and the other impulser produces an impulse for each fifth positive wave of current and by applying these impulses to a dynamo-meter type structure an effective impulse is produced only for each twentieth impulse of positive polarity.

Other objects, purposes and characteristic features of the present invention will be in part more particularly pointed out hereinafter and is 30 in part obvious from the accompanying drawing in which—

Fig. 1 and 2 illustrate modifications of a master clock embodying the present invention.

Fig. 2A is an enlargement of a portion of the master clock shown in Fig. 2; and

Fig. 2B illustrates a plan view of the mercury tube contactor shown in side elevation in Fig. 2.

The master clock shown in Fig. 1 utilizes a two-speed, self-starting, synchronous motor so designed as to operate at one synchronous speed for low voltage excitation and at a higher synchronous speed for high voltage excitation. The motor is utilized in the following way. During a power failure the secondary clocks are not operating, so immediately after a power failure, when this motor is used in a secondary clock, high voltage is fed to the secondary clock for the right length of time to bring it up by the amount which was lost during the power failure. However, as 50 shown, this motor is not used in a secondary clock.

Referring now to the master clock of Fig. 1. Pendulum 117 with a heavy bob 120 is supported at pivot 118. Bumper 122 is so positioned as to restrict the amplitude of pendulum 117. Pendu-

lum 117 is actuated by spring 123 supported or hooked on eccentric pin 115. Eccentric pin 115 is supported on gear wheel 113 which is driven through gear train 110, 111 and 112 by self-starting synchronous motor SM⁴. This gear train drives gear 113 at the same speed as the natural frequency of pendulum 117. The pendulum 117 carries a side arm. This side arm by a pin supports a flipper 135 which is freely pivoted thereon and has its center of gravity below the pin. In juxtaposition to the flipper 29 is a contact trigger 138 provided with a notch 136. When contact 138 is raised due to the engagement of flipper 135 in notch 136 it actuates the contact 138 in engagement with stationary contact 139.

The remainder of the master clock proper of Fig. 1 consists of a clock gear train and a ratchet mechanism. Pendulum 117 carries a spring actuating lever 124 actuated through spring 123 and pivoted at the top. Limit pins 125 limit the stroke of the actuating lever 124. Lever 124 carries ratchet pawl 126 which actuates ratchet wheel 128 with aid of stationary pawl 127. Ratchet wheel 128 drives clock hands 134 through gear train 130, 131 and 132.

Fig. 1 structure

In Fig. 1 is illustrated a master clock to be used in connection with the system shown in Fig. 1.

Referring now to Fig. 1, self-starting synchronous motor SM⁴ through gear train 110-112 drives gear wheel 113 having an eccentric pin 115 upon which is supported a spring 116 under tension. Spring 116 is connected to pendulum 117 and acts thereon. Pendulum 117 is supported from pivot 118 and has a heavy bob 120. A resilient bumper 122 including a rubber knob 121 is provided to limit the amplitude of the pendulum 117.

A spring 123 connects lever 124 and pendulum 117. Limit pins 125 limit the motion of lever 124. Pawl 126 is pivoted to lever 124 and actuates ratchet wheel 128 with the aid of stationary pawl 127. Pins 127 guide ratchet 126 and serve to prevent overthrow of the ratchet wheel 128. Ratchet wheel 128 through gear train 130-132 drives clock hands 134 of which for convenience only one is shown.

Referring again to Fig. 1, the pendulum 117 carries a flipper 135 which is pivoted thereto and which is in juxtaposition to a notched block 136 attached to contact member 138. Contact 138-139 completes the circuit from battery BA² through electro-magnet MG² which acts on armature 141 supported on pendulum 117.

Operation of master clock Fig. 1

The operation of the master clock portion of Fig. 1, namely, the elements having reference numbers 110 to 134, can be conveniently considered under two separate headings, firstly normal operation, and secondly operation during power failure. We will first consider the normal operation. The synchronous motor SM⁴ through gear train 110-112 drives gear wheel 113 supporting eccentric pin 115. This sinusoidal motion of pin 115 through spring 116, which is always under tension, impresses a sinusoidal force on the pendulum 117. As is shown in the theory of mechanics, this causes a vibration having the same period as the impressed force to be set up in the pendulum 117. The strength of the spring 116 is so adjusted that the amplitude of the resultant vibration is so great for ordinary variation in

frequency that the flipper 135 completely clears the block 136 on the swing to the left so that on the return swing to the right the flipper does not catch in the notch of this block 136. Thus under normal operation the contact 138 remains in the normal position and the battery BA² is not used. The bumper 121-122, although not essential, is preferably used for reasons given below. In practice the strength of the spring 116 is so adjusted as to cause the amplitude of the pendulum 117 to be great enough to strike the bumper 122 having a rubber impactor 121. This effectively limits the amplitude of the pendulum 117 and not only protects the clock from damage due to too great an amplitude but which also enables the clock to operate over a greater variation in frequency of the alternating current.

Coming now to the second phase of the operation of the master clock in case of power failure the synchronous motor SM⁴ stops and the spring 116 no longer exerts the above mentioned sinusoidal force. The pendulum now operates as an ordinary damped pendulum slowly decreasing in amplitude. The pendulum bob 120 is made very heavy so as to cause this decrease in amplitude to be very slow. That is, in case of power failure the synchronous motor SM⁴ stops and the pendulum 117 operates as a free damped pendulum. The amplitude of pendulum 117 decreases until the flipper 135 fails to completely clear the block 136, and on the return swing the flipper 135 catches in the notch of the block 136 and actuates the contact 138-139 to circuit closing position. The circuit from the battery BA² through contacts 138-139 to the electro-magnet MG² is thereby closed and the magnet MG² is energized. This causes the magnet MG² to attract the armature 141 and so give the pendulum an impulse to increase its amplitude. The amplitude is now great enough so that the flipper 135 clears the block 136 for a number of swings of the pendulum after which, due to reduction in amplitude, the above process is repeated. The flipper 135 and block 136 are so proportioned and positioned that the impulse given to the pendulum 117 comes near the center of the swing producing little phase shift in the pendulum. Whatever phase shift is produced is compensated for by adjusting the pendulum fast or slow by the right amount to compensate for this effect and to cause the structure to constitute a very accurate time piece mechanism.

Fig. 2 structure

The structure shown in Fig. 2 is a master clock similar to the one shown in Fig. 1. For convenience the clock train, hands, and ratchet actuating mechanism which is identical to that shown in Fig. 1 (123-134) is omitted from Fig. 2.

Referring now to Fig. 2, the pendulum 142 carries a heavy bob 143, and is supported on knife edge bearings 144-145 (enlarged in Fig. 2A). Pendulum 142 carries a coil 147 (Fig. 2A) rigidly fixed thereto and having its magnetic axis horizontal. In juxtaposition to the coil 147 is a stationary electro-magnet 148. The coil 147 and electro-magnet 148 are connected on one side in common to one side of the condensers C¹ and C² and on the other side independently through the neon glow lamps G¹ and G², respectively, to the other side of condensers C¹ and C². Condensers C¹ and C² are charged through the medium of rectifiers r¹ and r² through circuits including resistances R¹ and R² from A. C. power lines delivering alternating current of regulated frequency.

Supported on the pendulum 142 is a glass tube 149, shown as a top view in Fig. 2B. It contains inert gas and a globule of mercury 150, or it may be evacuated. Sealed into the middle arm of this tube 149 are the contact points 151. The contact points 151 when shunted by mercury globule 150 complete a circuit from the battery BA³ to the electro-magnet MG³ acting on armature 153 fixed to pendulum 142. Bumper 154 including a rubber impactor 158 is provided as in Fig. 1.

Fig 2 operation

The normal operation of the device shown in Fig. 2 is quite different from that shown in Fig. 1. Instead of a sinusoidal force being applied to the pendulum through a spring, periodic impulses are applied through the medium of the simultaneous discharge of the condensers C¹ and C² through glow lamps G¹ and G². The operation during power failure is very similar, at least in function, to that of the device shown in Fig. 1. Let us consider first the normal operation.

Referring to Fig. 2, the condensers C¹ and C² are charged through the rectifiers r¹ and r² and resistances R¹ and R² until the striking potentials of the glow lamps G¹ and G² are reached at which time the condenser is discharged through a glow lamp and the process is repeated. The resistances R¹ and R² are so adjusted that the one condenser is discharged, say, every fourth cycle while the other is discharged, say, every fifth cycle. Thus every twenty cycles the condensers are simultaneously discharged. Condenser C¹ is discharged through glow lamp G¹ and coil 147, while condenser C² is discharged through glow lamp G² and the winding of magnet 148. The coil 147 and magnet 148 taken together form a unit which is very similar to the watt-meter or dynamometer and a torque is experienced only when the coil 147 and magnet 148 are simultaneously energized. Thus every twentieth cycle the pendulum receives an impulse. These impulses have the same effect on the pendulum as a spring impressing sinusoidal forces on the pendulum since the fundamental Fourier component is the only one having much effect on the pendulum. The bumper 154 has the same function as in Fig. 1.

The operation during power failure is quite similar to that of Fig. 1, the only difference being that the flipper 135 and contacts 138-139 of Fig. 1 are replaced by the tube 149. The tube 149, as can be seen in the drawing is warped so that the sinusoidal motion of the pendulum will cause the mercury to move around the circuitous tube. When the amplitude is large the globule will be moving rapidly when it passes the opening of the short cut branch (see Fig. 2B) so that the globule will follow the outside branch. However, when the amplitude has fallen to the correct value the mercury globule will be moving so slowly that it will enter the short cut branch of the tube and in passing through it will momentarily short circuit the contact points 151 resulting in the energization of the magnet MG³ and this gives the clock an impulse to increase its amplitude for several pendulum swings during which the mercury 150 takes the long path after which the above process is repeated.

It is thus seen that in the master clocks illustrated in each of Figs. 1 and 2 the alternating current not only functions to dominate the pendulum but it also serves as a cut-out device to cut out the local source of energy, in the form

of a battery, so that no power-off relay such as would ordinarily be used is required.

The applicants have thus shown and described several forms of their invention including modified forms of master clocks, and it should be understood that the master clocks illustrated have been selected to aid in the description of the principles employed and some manners in which these principles may be applied in practicing the invention, and that the invention is not limited to the particular constructions illustrated. It should therefore be understood that the present invention is not limited to the specific constructions illustrated except as demanded by the scope of the following claims.

What we claim as new is:

1. In a sustained power clock, the combination with a source of alternating current having its frequency regulated to correctly manifest the passing of time, an oscillatory member having a natural frequency of oscillation to substantially correctly manifest the passing of time, a two element electro-magnet so associated with said member that if intermittently rendered active at approximately the natural frequency of said member will cause said member to oscillate with said intermittent activities, a condenser and an electronic discharge device connected in series with each of the two elements of said electro-magnet, a rectifier and charging resistances connected in series and to said source of alternating current for each of said condensers for intermittently charging said condensers, the condensers and resistances being so constructed and proportioned that one of said electron discharge devices discharges its associated condenser once for each predetermined number of cycles of alternating current and the other electron discharge device discharges its associated condenser once for each but a different predetermined number of cycles of alternating current, whereby said electro-magnet is rendered active only once during the product of the two predetermined number of cycles of alternating current to cause said member to be oscillated in sub-synchronism with said alternating current, and means including a local source of energy for maintaining said member oscillating during a current cessation.

2. In a clock; the combination with a source of alternating current of regulated frequency, regulated to correctly manifest by cycle summation the passing of time; a pendulum having a natural frequency which is slightly less than a sub-multiple of the average frequency of said current; a coil which when energized may act on said pendulum; means for applying electric current impulses to said coil including a condenser, an electronic discharge device and said coil in series, and a rectifier for charging said condenser from said source of alternating current; and means including a local source of energy for maintaining said pendulum oscillating at or above a predetermined amplitude during a current cessation.

3. In a combined direct and alternating current clock, the combination with a time shaft, means including an oscillatory device which if oscillated advances said shaft directly in accordance with its frequency of oscillation, means including a direct current source for oscillating said oscillatory device at its natural frequency and at an average medium amplitude and which consumes no direct current energy if said oscillatory device is oscillated at a higher amplitude, said oscillatory device having a natural frequency to

cause the rotation of said time shaft to substantially correctly manifest the passing of time, a source of alternating current having its frequency regulated to correctly manifest the passing of time, and means controlled by said source of alternating current for doing both oscillating said oscillatory device at or above said higher amplitude so that no direct current will be consumed and oscillating said oscillatory device in consonance with the frequency of said alternating current so that said time shaft will correctly manifest the passing of time so long as no alternating current cessation occurs, said last mentioned means including a condenser and a discharge device said condenser being charged from said alternating current source to a predetermined potential in a predetermined number of cycles which is discharged through said discharge device upon reaching said potential.

4. An all electro-magnetic oscillatory mechanism, operating means for operating such mechanism in subsynchronism with an alternating current when such current is available and for operating it from a local source of current when such alternating current fails comprising, an oscillatory mechanism, a source of alternating current, condenser charging and discharging means producing a flow of current once for each predetermined number of cycles of said alternating current, condenser charging and discharging means producing a flow of current for each predetermined but different number of cycles of said alternating current, means producing a magnetic pull upon said oscillatory mechanism only when both of said means produce a flow of current simultaneously, and other wholly electro-magnetic means for applying a magnetic actuating force upon said oscillatory mechanism when its amplitude of operation falls below a predetermined value.

5. An all electro-magnetic oscillatory mechanism, operating means for operating such mechanism in subsynchronism with an alternating current when such current is available and for operating it from a local source of current when such alternating current fails comprising, an oscillatory mechanism, a source of alternating current, condenser charging and discharging means producing a flow of current once for each predetermined number of cycles of said alternating current, condenser charging and discharging means producing a flow of current for each predetermined but different number of cycles of said alternating current, means producing a magnetic pull upon said oscillatory mechanism only when both of said means produce a flow of current simultaneously, an electro-magnet which when energized acts upon said oscillatory mechanism, a local source of current, and a mercury contact mechanism which momentarily connects said local source to said electro-magnet at a predetermined point in the swing of said oscillatory mechanism only if the amplitude of operation of said oscillatory mechanism falls below a predetermined value.

6. In an all electro-magnetic oscillatory mechanism operating means, the combination with an oscillatory mechanism, a local source of current, an evacuated container having two circuitous paths, a globule of mercury in said container, said container being so shaped that when mounted to operate with said oscillatory mechanism said mercury will circulate through one of said paths so long as said oscillatory mechanism oscillates at an amplitude above a predetermined value and

5 will circulate through the other of said paths when the amplitude of oscillation of said mechanism falls below said value, contacts sealed into said container to be shunted by said mercury when said mercury passes through said other path but not when it passes through said one path, an electro-magnet for when energized exerting a force upon said oscillatory mechanism, and a circuit including said local source said contacts and said electro-magnet in series.

7. In all electro-magnetic oscillatory mechanism operating means, the combination with an oscillatory mechanism, a local source of current, an evacuated container having two circuitous paths, a globule of mercury in said container, said container being so shaped that when mounted to operate with said oscillatory mechanism said mercury will circulate through one of said paths so long as said oscillatory mechanism oscillates at an amplitude above a predetermined value and will circulate through the other of said paths when the amplitude of oscillation of said mechanism falls below said value, contacts sealed into said container to be shunted by said mercury when said mercury passes through said other path but not when it passes through said one path, an electro-magnet for when energized exerting a force upon said oscillatory mechanism, a circuit including said local source said contacts and said electro-magnet in series, a source of alternating current of regulated frequency, and an all electro-magnetic means governed from said source of alternating current and acting to control said oscillatory means to operate it in subsynchronism with the frequency of said alternating current at a sub-frequency such that one cycle of the sub-frequency includes the product of the cycles in each cycle of two higher sub-frequencies of said alternating currents which higher sub-frequency each includes a plurality of cycles of said alternating current, whereby said first mentioned sub-frequency has a cycle time which is the product of the cycle times of the two higher sub-frequencies.

45 8. An all electro-magnetic oscillatory mechanism operating means for operating such mechanism in subsynchronism with an alternating current when such current is available and for operating it from a local source of current when such alternating current fails comprising, an oscillatory mechanism, a source of alternating current, two circuits, means for causing current flow in one of said circuits once only for each predetermined number of cycles of said alternating current, means for causing current flow in the other of said circuits only once for each predetermined but different number of cycles of said alternating current, electro-magnetic means responsive only when both of said circuits have current flow therein simultaneously for applying an actuating force on said oscillatory means, and other electro-magnetic means including means controlled in accordance with the amplitude of oscillation of said oscillatory mechanism for applying an actuating force to said oscillatory mechanism when its amplitude of operation falls below a predetermined value.

60 9. An all electro-magnetic oscillatory mechanism operating means for operating such mechanism in subsynchronism with an alternating current comprising, an oscillatory mechanism, a source of alternating current, a first and a second circuit, means for causing the flow of current in said first circuit once only for each predetermined number of cycles of said alternating

current, means for causing the flow of current in said second circuit only once for each predetermined but different number of cycles of said alternating current, means responsive only when both of said circuits have current flow therein simultaneously for applying an actuating force on said oscillatory means, and means for keeping said oscillatory mechanism operating during a cessation of alternating current.

10. An all electro-magnetic oscillatory mechanism operating means for operating such mechanism in synchronism with an alternating current when such current is available and for operating it from a local source of current when such

alternating current fails comprising, an oscillatory mechanism, a source of alternating current, condenser charging and discharging means producing a flow of current once for each predetermined number of cycles of said alternating current, condenser charging and discharging means producing a flow of current for each predetermined but different number of cycles of said alternating current, and electro-magnetic means for producing a magnetic pull upon said oscillatory mechanism only when both of said means produce a flow of current simultaneously.
